UNITED STATES PATENT OFFICE.

FERDINAND PHILIPS, OF PHILADELPHIA, PENNSYLVANIA.

BOLT-HEADING MACHINE.

SPECIFICATION forming part of Letters Patent No. 334,465, dated January 19, 1886.

Application filed November 16, 1885. Serial No. 182,964. (No model.)

To all whom it may concern:

Be it known that I, FERDINAND PHILIPS, a subject of the Emperor of Germany, but domiciled in the United States, at the city of Philadelphia, in the county of Philadelphia and State of Pennsylvania, have invented certain new and useful Improvements in Bolt-Heading Machines, of which improvements the following is a specification.

10 My invention relates, generally, to that class of bolt-heading machines in which the blank to be headed is held firmly by one end in a die or holder, while the end of the blank upon which the head is to be formed projects in such manner as to admit of its being operated upon, when heated to the proper temperature, by a series of hammers which successively work it endwise and laterally to a square or hexagonal or other shape, as is well understood. The 15 hammer acting upon the blank endwise or in the direction of its axis and upsetting the projecting end of the blank is called the "header," as fully explained in an application for Letters Patent of the United States filed by me 20 on the 2d day of April, 1885, in which application, as aforesaid, the hammers and their mode of operation are fully explained, while my present invention relates more particularly to certain features and parts of a bolt- 25 heading machine—such, for instance, as the dies for holding the bolt-blanks—their adjustments relatively to the header, and their *modus operandi*; and it further embraces features and parts, the construction, arrangement, and 30 operation of which will be hereinafter fully explained, and designated in the claims. For convenience of reference I shall allude to the several parts by assigning to them such technicalities as are recognized in general practice.

Bolt-heading machines, as have heretofore been constructed, comprise two separate and distinct classes. First, those in which the blank dies have a fixed position in the machine and require of necessity a stoppage of the header after the completion of each bolt, to allow of the insertion of another blank between the dies; and, second, those in which the header has a continuous reciprocating motion imparted to it, and in which the blank dies are mounted upon a movable die-carriage, which is susceptible of being moved a sufficient

distance away from the header to permit of the insertion of a bolt-blank between the dies and afterward moved in the direction toward 55 the header close to the side hammers and to lock it there so that these hammers may operate upon the inserted blank.

As is well understood, many disadvantages have been encountered in the use of such machines. In the former class due to sudden jars and wear and tear of the machinery arising from being compelled of necessity to start the machine anew after the insertion of each bolt-blank, while in a different direction similar disadvantages have characterized the use 60 of machines comprised in the latter class, arising from the recognized fact that the center of the bolt-blank, which is the center of strain in the heading operation, always occurred some 65 distance above the center of resistance, which locked the die-carriage in this position, and thereby produced a leverage tending to lift the movable carriage from its seat during the heading operation, and likewise causing an 70 unpleasant vibration of the machine, which has proved more or less destructive to the accuracy of the bolt.

A full appreciation of the existing defects in machines of the character above mentioned, 8c and the determination to obviate these objectionable features and difficulties, led to a series of experiments resulting in the development of my present invention, whereby I am enabled to entirely overcome this difficulty 85 by laying the center of force required for heading and the center of resistance in the same plane. Furthermore, I am enabled to make due provision for the movement of the die-carriage with its dies to and from the 90 hammers with the expenditure of comparatively little exertion or effort on the part of the operator; and, furthermore, my invention embraces certain features in the operation of the machine, which will be hereinafter particularly pointed out and described.

In the accompanying drawings, illustrating my invention, Figure 1 is a sectional side view of a bolt-heading machine embodying my improvements. Fig. 2 is a detached view 100 of the spider and lower vertical hammer. Fig. 3 is a plan view of the die-carriage and dies for holding the bolt-blank, showing their arrangement and operation. Fig. 4 is a side

elevation of the same. Fig. 5 is a transverse section on line $x-x$ of Fig. 1. Fig. 6 is a longitudinal section through the line $y-y$ of Fig. 5. Fig. 7 is a front view of the die-carriage 5 with the frame of the machine shown in section. Fig. 8 is a plan view of Fig. 7, and Figs. 9 and 10 are respectively detached views from both sides of the machine, showing details of the mechanism for actuating the die-carriage.

Referring to the drawings, a and a' are the blank-dies. These dies are pieces of steel so shaped as to fully surround the blank when closely pressed together, and are mounted on 15 slides b and b' , which are in turn moved in guides forming part of the die-carriage D, and held in position thereto by caps c , c' , c'' , and c''' . When the bolt-blank h is in position to be acted upon—that is, gripped by the dies 20 a and a' —the end opposite the one on which the head is to be formed rests against an adjustable abutment-screw, g . This abutment-screw g being located in the center of the bolt, and, therefore, in the center of the strain put upon 25 the machine during the heading operation, has been the principal element heretofore forbidding the introduction of a locking device for the die-carriage whereby the die-carriage might be locked central with the bolt. I over- 30 come this difficulty and lock the die-carriage in position by means of a fork-shaped wedge, d and d' , straddling the blank abutment, as shown in Figs. 5 and 6. This bifurcated wedge d and d' abuts against the frame A of the machine, locking the die-carriage D by means of 35 tapering faces pressing against steel abutments f and f' of the die-carriage, as shown in Figs. 6 and 8, and their situation is such that the pressure of the header against the dies a and 40 a' is transmitted in the same horizontal plane with the abutments f and f' , and against the wedges, thereby obviating the production of leverage and so preventing the die-carriage from being lifted off its seat. This has not 45 before been accomplished because the locking device has been in all cases either a small crank connected with the die-carriage below the center of the bolt-blank moving the die-carriage into position and locking it when 50 on its center, or it has been accomplished by means of a single wedge entering the die-carriage, but remaining below the center of the bolt-blank. In all cases, however, leverage has proved unavoidable, which is now en- 55 tirely overcome.

A further feature of my improved bolt-heading machine embodies certain mechanism for holding the bolt-blank and for gripping it firmly during the heading operation. It em- 60 braces in conjunction therewith certain devices, by means of which the center of the bolt-blank may be readily and effectively adjusted to a central position with the header.

As above mentioned, blank-dies a and a' are 65 mounted on slides b and b' , which slide in guides b^2 and b^3 , forming part of the die-carriage D, and are held in position by caps c, c' ,

c'' , and c''' . Each die-holder slide is provided at the end opposite the die-holding fork with toggle-joints t and t' , respectively. These toggle-joints t and t' are jointed to movable blocks s and s' , rigidly secured in the arms q and q' , which are continuations of the guides b^2 and b^3 . At the ends of these arms q and q' are set-screw blocks q^2 and q^3 , provided with set-screws q^4 and q^5 , the function of these screws q^4 and q^5 being to move the whole system of blocks with the toggles and die-slides together with the dies horizontally at will until the required position is obtained. The established 70 practice has heretofore been to pack behind the dies a varying number of layers of sheet-tin—that is to say, packing more or less behind each die, and shifting the tin-plate from one to the other until the center of the die occupied a central position with the header. This operation required not only a stoppage 80 of the machine for its performance, but necessarily required the consumption of a considerable amount of time for the setting, and in 90 actual practice it has proven not sufficiently accurate for general work.

In order to open and close the dies a and a' , I connect the toggles t and t' with arms z and z' of the bell-crank levers r and r' , respectively, 95 which have their fulcrums f^2 and f^3 in arms q and q' , forming part of the die-carriage, while the arms z and z' , provided with rollers z^2 and z^3 , move upon the surface of the cams u and u' . One portion of these cams u and u' is 100 almost parallel with the center of the machine, while the other portion converges backward toward the center of the machine. When the die-carriage moves in the direction of the arrow, as shown in Fig. 3, the bell-crank levers 105 r and r' , having their fulcrums f^2 and f^3 upon the arms of the die-carriage D, move with said carriage, and consequently the rollers z^2 and z^3 pass over the parallel portions of the cams u and u' , which are fastened to the main frame 110 A of the machine and remain stationary. During this portion of the movement of the die-carriage D the dies a and a' remain in their closed position. When the die-carriage moves farther, the bell-crank levers r and r' 115 are forced to follow the inclined portion of the cams u and u' by counter-cams v and v' , and when the die-carriage is in its remote position from the hammer the dies are fully 120 opened by the action of the bell-cranks acting upon the toggles connected with the die-holding slides. On the other hand, when the heated blank is placed between the open dies and the die-carriage D is moved forward toward the hammers the dies will partially close as the rollers fastened on the end of the bell-crank levers r and r' mount the inclines of the cams u and u' , and when they 125 reach their greatest height the dies are closed; but, however, in this position of the bell-cranks the die-carriage is only midway in the direction of the hammers. For the other portion of the forward movement of the die-carriage 130 D the cams diverge slightly from the

center of the machine, and this serves to give a powerful grip to the bolt-blank aided by the favorable position of the toggles, which are nearly straight when the die-carriage is about 5 half-way up. When the die-carriage is in its operative position, the blank is held so firmly that a minimum amount of material will flow between the dies while the blank is upset and is being worked by the hammers, thereby obviating one of the most common faults existing in bolts made in open dies.

A further important feature of my invention consists in the automatic mechanism for moving the die-carriage. In a small machine 15 I generally operate the die-carriage by a pulling-wedge with a foot-lever, and move the carriage itself by a hand-lever; yet, in large machines, where the parts are more ponderous, I prefer the automatic mechanism; and it consists of devices for pulling the wedges and 20 subsequently moving the carriage, and so arranged that the carriage may remain unlocked for an indefinite length of time for the reception of a new bolt-blank, or it may remain locked 25 for any suitable length of time for different sizes and kinds of bolts to be headed, at the option of the attendant in charge of the machine.

Machines have been constructed in which 30 the heading, opening, and closing are automatically timed. This, however, I desire to avoid, as it is inadequate for bolt-works, due to the variety and character of the work done and the irregular heating of the blanks, which 35 cannot well be avoided.

The mechanism for producing the desired result will now be described.

The bifurcated wedge d and d' is held in position and locked by means of a spring, d^2 . 40 A lever, 1, mounted upon a shaft, 3, engages with the same, while a second lever, 2, upon the same shaft 3, is actuated from an eccentric on the main driving shaft N of the machine, through mechanism commonly called a "Cor- 45 liss Trip-Motion," 6, whereby the bifurcated wedge can be moved, at the option of the attendant, as follows: The lever 4 being moved backward in the direction of the arrow, as shown in Fig. 4, permits the crow-claw 6, 50 resting upon the cam 5, to drop a sufficient distance to allow the tripping device 6 to engage with the lever 2, pulling the wedge downward. On the opposite side of the machine I arrange similar mechanism actuating 55 a sector, 7, upon shaft 11, by means of a lever, 10, and in connection with the sector 7 is the rack 8, attached upon the under side of the die-carriage D, and lever 10, actuated by the cam 9 in connection with the cam 5 on one 60 shaft, and both cams so timed relative to the header and to each other that the wedge is released just before the header delivers its blow upon the bolt-head endwise—that is to say, when the side hammers are clear of the 65 bolt-head. Immediately after the wedge is drawn the die-carriage D moves backward,

the dies open, and the finished bolt drops out. When the dies are to be closed, the operator moves the hand lever 4 in the opposite direction to that of the arrow, as shown in Fig. 4, 70 thereby releasing the tripping device 6 on the lever 2, and at the same time reverses the action of the tripping device actuating the sector 7, and the carriage is then moved toward the hammers, holding the new blank in a 75 gripped position, while the header is moving away from the blank.

When the die carriage D is in the desired position, the bifurcated wedge d and d' springs into position through the action of the spring 80 d^2 locking the die-carriage D.

The double action of the mechanism for opening and closing the dies, which is identical with moving the die-carriage D, is fully illustrated in Fig. 10; and it will be readily 85 observed that the tripping device 12 is double-acting, according to the position of the cam 9, and will either engage with the lever 10 when moving in the direction from right to left, or vice versa, or not at all when in a central position.

The attendant desiring to withdraw the die-carriage pulls lever 4 in the direction of the arrow, Fig. 4, and locks its latch in the notch 16. The tripping devices 6 and 12 will now 95 engage with their respective levers 2 and 10 by gravity and in proper succession. On the other hand, if he desires to lock the carriage, it is accomplished by locking lever 4 in the notch 17. In order to make due provision 100 for any possibility that trip 12 may not be in the proper position to engage with the lever 10, the power exerted by the attendant will be stored up in the spring 18, so that when by the continued motion of this tripping de- 105 vice 12 the position is reached whereby it can freely rise to engage with the lever 10, it will do so by the action of this spring 18 in conjunction with the counter-weight 19.

Having thus described the nature and objects of my invention, what I claim as new, and desire to secure by Letters Patent, is—

1. In a bolt-heading machine, a movable die-carriage locked in position by means of wedges entering the die-carriage up to or beyond the center line of the bolt-blank, substantially as and for the purposes described.

2. In a bolt-heading machine, a movable die carriage provided with guides for the die-holders, in combination with die-holders, the latter being connected to toggles adjustable in arms of said die-carriage and operated by levers pivoted to the die-carriage, and actuated by endwise motion of said die-carriage through cams having a fixed position on the bed of the machine, substantially as and for the purposes described.

3. In a bolt-heading machine, a movable die-carriage, in combination with die-holders, the bell-cranks and cams and counter-cams so arranged as to hold the bolt-blank during one portion of the endwise motion of the die-

carriage, and releasing the blank during the remaining portion of its movement, substantially as and for the purposes described.

4. In a bolt-heading machine, the combination of a movable die-carriage, D, of bifurcated wedge d d' , with spring d^2 , of lever 12, shaft 3, hand-lever 4, cam 5, trip mechanism 6, and main driving-shaft N, substantially as and for the purposes described.

10 5. In a bolt-heading machine, the combination of a movable die carriage, D, with rack 8, sector 7, shaft 4, lever 10, double-acting trip mechanism 12, main driving-shaft N, cam 9, shaft 13, pinion 14, segment 15, lever 4, 15 spring 18, and counter-weight 19, substantially as and for the purposes described.

6. In a bolt-heading machine, mechanism for operating the die-carriage, consisting of lever 4, spring 18, segmental lever 15, pinion 14, cam 5, shaft 13, cam 9, and tripping devices 20 6 and 12, operated from the main driving-shaft N, and all arranged and operating in proper succession, substantially as described.

In testimony whereof I have hereunto set my hand in the presence of two subscribing 25 witnesses.

FERDINAND PHILIPS.
